UNITED STATES PATENT OFFICE.

FRANK B. COMINS, OF NEWTON, AND JOSEPH ARMSTRONG, OF MALDEN, MASSACHUSETTS, ASSIGNEES TO AMERICAN MOISTENING COMPANY, OF BOSTON, MASSACHUSETTS, A CORPORATION OF MAINE.

RESTRICTION VALVE.

Application filed May 28, 1921. Serial No. 473,331.

To all whom it may concern:

Be it known that we, FRANK B. COMINS and JOSEPH ARMSTRONG, citizens of the United States, residing at Newton and 5 Malden, respectively, in the county of Middlesex and State of Massachusetts, have invented certain new and useful Improvements in Restriction Valves, of which the following is a specification.

This invention relates to improvements in 10 restriction valves. More particularly it relates to devices by which a passage may be provided for a desired minute flow of fluid such as compressed air from a source of 15 supply, the passage being, for example under one one-hundredth of an inch in diameter. Such passages are liable to become clogged by solids carried by the fluid, in 20 spite of all filtering precautions which may be taken; and the parts involved are so delicate in dimension, and relatively weak in consequence that the attention of an expert is required usually to adjust and maintain 25 them in satisfactory working order. The present invention has been devised to improve 30 that form of apparatus of this type which is used in connection with automatic control apparatus for operating a relay valve which, by apparatus not necessary to be described here, is arranged to be actuated 35 by the same supply of fluid energy—in this case compressed air—which furnishes the stream of fluid that is to pass through the restriction valve. The term "restriction 40 valve" is used herein because it is a term known in the trade, although it is a misnomer to a degree, the function is not that of a valve, to open and close a passage, but rather is merely that of a restricting element to fix the size of a passage. On account 45 of the danger of clogging, it is desirable to have this element removable for cleaning purposes. Heretofore, in one arrangement on which the present invention 50 is an improvement, a tapering pin has been used, having a diameter ranging from five hundredths of an inch downward, and having a scratch in its surface constituting the passage for such restricted flow of air as 55 is desired. In the handling of such pins, when installed in apparatus on the premises of users in factories and elsewhere, it is found that the workman who removes the pin for cleaning purposes, is liable to drive

it in too far, and to bend it, thereafter having trouble in getting it out again for cleaning; or, because of its size, he is liable to lose it. The present improvement provides a pin having a determinate limit of insertion; capable of being held at its limit by a screw thread, the pin striking the limit as an abutment, rather than as a wedge; and therefore coming away freely without sticking upon being unscrewed. The restricted passage is constituted by providing 55 a groove or scratch of the desired depth in the head of the pin which bears against the abutment that stops its insertion.

The invention may be applied in various forms, a typical one of which is illustrated 70 in the accompanying drawings; but it should be understood that the patent is not limited to the arrangement herein described. It is intended to cover by suitable expression 75 in the appended claims whatever features of patentable novelty exist in the invention disclosed.

In the accompanying drawings;

Figure 1 illustrates an embodiment of the invention, which may be considered to be a 80 side elevation of a medial section, greatly enlarged;

Figure 2 is a plan of the same with the cap and supporting means removed;

Figure 3 is a plan of the valve casing with 85 the valve removed;

Figure 4 is an elevation of said valve casing;

Figure 5 is a plan of the valve;

Figure 6 is a side elevation of the valve; 90 and

Figure 7 is a bottom plan of the same.

Referring to the drawings, 10 indicates a portion of a passage for a fluid whose flow is to be restricted. In the case represented 95 this passage may be assumed to be a piece of small copper tubing 11 set into a block 12 in which is a passage 101 in continuation of the passage 10 leading to a central chamber 13 formed by drilling axially through 100 the block. This chamber may be filled with suitable fibrous material 26 adapted to retain any solid matter entering the chamber through the passage 10. A plug 27 at the bottom of the cavity 13 may be readily removed to permit renewal or cleaning of the filtering material. At its other end, the cavity 105 opens into a larger cavity or hole 14,

which is formed in the block 12 on the same axis as the chamber 13. This hole may be filled with the entering end of the valve casing 15, making such a tight fit when pressed therein as to be held securely in place by friction. This casing has an axial chamber 16 with an inlet 17 through the middle of its conical bottom communicating with the chamber 13, and an opening 18 in its side adapted to register with a passage 18' through the block 12, to constitute a discharge passage from the chamber 16; there being a piece of copper tubing 20, arranged in the block similar to the tubing 11 for carrying restricted flow of fluid. The restriction is effected by means of a valve whose face 21 is adapted to seat on the chamber bottom to close the greater part of the inlet 17, or, in other words, to close abruptly the inlet 17 except for a restricted passage. There is a restricted passage 25 provided along the surface of the face 21, as by a file mark; but except for this, or such equivalents of this as may be provided, the face 21 closes the escape passage 17 from the chamber 13. The hemispherical face 21 of the valve is pressed against the conical bottom of the axial chamber 16 in the casing by the valve stem 22, whose threaded top portion 23 is screwed into the outer end of the casing by aid of its knurled head 24.

The hemispherical face of the valve makes only a line contact with the conical surface of the seat, and this is a marked improvement over the surface contact of the hereinbefore mentioned tapering pin type of valve. In the latter, the restricted passage is necessarily of appreciable length, difficult to make accurate, and easily clogged when in use since any solid matter, however small, entering the restricted passage must naturally strike against the walls thereof, and be slowed up by the frictional resistance of such engagement, which if repeated as often as occurs during the length of travel along the relatively rough surface of a tapering pin must finally stop such a small particle,

and thereby in time clog the passage. With the improved line contact of the present invention no length of restricted passage is created, because the abutments are in contact around a horizontal circle, at some point of which a notch is cut for the opening past the otherwise sealed abutments, and any minute particle flowing along with the air readily passes through the notched opening in the line of contact; and will be blown through if it has tendency to lodge there, reaching space of freer dimensions as soon as it has passed what would be merely the entrance in a restricted passage.

After being seated the valve is protected by covering the valve head with a cap 28 fastened externally to the valve casing. The arms 29 and nut 30 represent any suitable fastening means for holding the apparatus in position.

When in operation, air flows through the passage 101 from the supply tube 11 into the filtering chamber 13, thence through the inlet 17 along the scratch 25 on the valve face to the valve chamber 16 from which it discharges through the opening 18 and passage 18' into the tube 20 along which it continues to the mechanism to be operated by it.

We claim:

The combination, in a fluid passage, of a filtering chamber; a cylindrical valve chamber with axial openings one of which constitutes the entrance from the filtering chamber, and with a lateral discharge opening; a valve in the valve chamber, comprising a stem having at one end a surface adapted to close abruptly the said entrance except for a channel continuously permitting restricted flow, and having at its other end means removably engaging the sides of the valve chamber, adapted both to close the other axial opening and to support the stem.

Signed at Boston, Massachusetts, this 23rd day of May, 1921.

FRANK B. COMINS.
JOSEPH ARMSTRONG.
